SCOOP REMOVAL PLIERS

Louis H. Morin, Bronx, N. Y.

Application May 2, 1945, Serial No. 591,512

4 Claims. (Cl. 153—1)

1

This invention relates to pliers designed for the removal of scoops from the stringers of separable fasteners. More particularly the invention deals with a hand operated tool of the type defined wherein individual scoops may be engaged and simultaneously severed from the stringer tape and moved into position spaced from the beaded edge of the tape for displacement from the tool preparatory to a second removal operation. The novel features of the invention will be best understood from the following description when taken together with the accompanying drawing, in which certain embodiments of the invention are disclosed, and in which the separate parts are designated by suitable reference characters in each of the views; and in which:

Fig. 1 is a side view of a pair of pliers made according to my invention, indicating the first position in the use thereof for removing a scoop.

Fig. 2 is a section on the line 2—2 of Fig. 1.

Fig. 3 is a longitudinal sectional view through the pliers showing the jaw members thereof in a different position from that shown in Fig. 1; and

Figs. 4 and 5 are other detailed views of the jaw end of the plier showing the next successive operations thereof in the stripping or severing and removal of a scoop.

In the drawing, 10 represents a main body portion of a pair of pliers having a handle member 11 and a jaw stop or body 12 from which extend two outwardly and upwardly directed wall portions 13 and 14. The wall portions 13 and 14 form what may be termed a U-shaped end on the body 10, and on the stop 12, is an upwardly extending rear wall portion 15, note Fig. 3.

Secured between the upper outer corner portions of the walls 13 and 14 is a stationary jaw 16 being held in place by two rivets, screws or other fastenings 17, the jaw having an outer inwardly curved hook-shaped end 18 terminating in a prong-like member 19. Pivotaly supported between the walls 13 and 14, as seen at 20, is a movable jaw 21. The jaw 21 has an outer end which is substantially similar to the jaw 16. In other words, is hook-shaped in form, as seen at 22, and terminates in a prong as at 23. The jaw 21 has an inwardly extending arm 24 having at its inner end a raised portion 25.

Slidably mounted within the walls 12 and 13, and between adjacent surfaces of the jaws 16 and 21, is a plunger 26, in the lower surface 27 of which is a recess 28 adapted to receive the projection 25, to allow the jaw member 21 to drop by gravity into the position shown in Fig. 1 of the drawing. The jaw member is moved into the

gripper position shown in Figs. 3, 4 and 5 of the drawing by engagement of the projection 25 with the surface 27 of the plunger. The upper surface of the plunger 26 is fashioned to form a short rack 29 adapted to be engaged by a gear segment 30 at the inner end 31 of a handle member 32, pivoted within and between the walls 13 and 14, as seen at 33. The handle member 32 has an offset portion 34 therein to clear the free end 10 of the reduced portion 35 of the plunger 26, as well as a sleeve 36 enveloping a coil spring 37 arranged on the end 35. A washer 38 is held seated upon the spring 37 by a nut 39.

The other or forward end of the plunger 26 has a substantially V-shaped socket portion 40, the walls of which terminate in inwardly extending retaining lugs 41.

It will be understood that the hook-shaped ends 18 and 22 of the jaws 16 and 21 are reduced in thickness in comparison with the remainder of the jaw members, as indicated by the bevelled wall portions 42 and 43, in order to adapt the prongs 18 and 22 to the width of the scoops employed, it being understood in this connection that a few different sized tools will be used for scoops of widely varying widths, particularly when it is desirable to remove a single scoop arranged between two adjacent scoops. However, when scoops are disposed at the ends of stringers, the relative width of the jaws and scoops is immaterial, providing the jaws are reasonably wide to engage at least the greater width of the scoops employed.

In Figs. 1, 3, 4 and 5, I have shown at 44 a stringer tape upon the beaded edge 45 of which is arranged a scoop 46. The scoop 46 includes side wall portions 47 and 48 arranged upon opposite sides of the tape and the bead 45 thereof.

In use, the tool is applied to the fastener stringer as shown in Fig. 1; that is, with the prong 19 resting on the tape and abutting the rear of the scoop 46 to be removed. In this position of the tool, the jaw 21 is open. The handles 11, 32 are then squeezed together as in using an ordinary pair of pliers, in which operation the rotation of the gear segment 30 advances the plunger 26 relatively to the jaws 16 and 21 and into the successive positions illustrated in Figs. 3 and 4. The sequence is such that the plunger first cams the lower jaw 21 into position to engage the tape and scoop, and then the base of the socket 40 strikes the free end of the scoop. As the plunger movement is completed, the scoop is driven bodily onto the inclined diverging surfaces 49 and 50 of the prongs 19 and 23, thereby

spreading the tape-engaging portions of the scoop in a manner similar to that shown in Fig. 4, in other words, in cutting or stripping the side portions 47 and 48 from the sides of the tape. It will be observed that in this process the side portions or walls 47 and 48 of the scoop are spread apart to such an extent as to engage them beneath the lugs 41 which overhang the mouth of the socket 40. In the result, when pressure on the handle member 32 is released, the spring 37 will withdraw the plunger from the jaws, carrying with it the scoop 46, as illustrated in Fig. 5. The removed scoop may now drop through the openings between the jaws or be manually forced therefrom. Upon completion of the above operation, the jaw 21 will drop into the position shown in Fig. 1, or may be moved into this position by hand. It will be understood that the wall 15 checks the movement of the plunger in one direction, as will appear from a consideration of Fig. 1. of the drawing.

The plunger 26 may be descriptively referred to as a movable anvil engaging the scoop end in forcing the scoop in the direction of the stripper tools, comprising the pronged ends 19 and 23, and the lugs 41 may also be said to comprise hook portions for engaging a stripped scoop in moving the stripped scoop away from the tape edge.

It will be understood that the gripping engagement of the jaw members or the curved ends 18 and 22 thereof with the tape is more or less of a supporting engagement simply to maintain the tape in position between the jaws and permit the movement of the prongs 19 and 22 from the position shown in Fig. 3 to that shown in Fig. 4, while at the same time, supporting the tape when the scoop is withdrawn, as illustrated in Fig. 5, in which operation the tape might slip to a slight extent between the jaws.

Having fully described my invention, what I claim as new and desire to secure by Letters Patent is:

1. A tool for stripping scoops from a separable fastener stringer tape comprising a member having a handle and a fixed jaw, a second jaw movably supported in said member, a plunger mounted in said member and arranged between said jaws, said plunger having a scoop engaging end which comprises a socket that is larger than said scoop, a spring normally supporting the plunger in spaced relation to said jaws, interengaging means on the movable jaw and on the plunger for maintaining said jaws open when the plunger is in said normal spaced relation to the jaws, means comprising a supplemental handle pivotally supported in said member and operatively engaging the plunger for manually moving the latter in the direction of said jaws and against the action of said spring, means on the plunger for moving the movable jaw to a closed position with respect to the fixed jaw when the plunger is moved against the action of said spring, and means on said jaws for expanding the scoop into said socket as the plunger moves the scoop toward said jaws, said spring being adapted to retract the plunger and engaged scoop upon release of said supplemental handle.

2. A tool for stripping scoops from separable fastener stringers, said tool comprising a body

portion having relatively movable jaws for engaging opposed surfaces of a stringer tape adjacent a scoop thereon, said jaws having reversely curved pronged ends terminating in diverging surfaces for spreading side portions of the scoop when the latter is forced against said pronged ends, a plunger arranged in said body portion between and movable toward and from said jaws, said plunger having a scoop engaging anvil adapted to force the scoop against said pronged ends during movement of the plunger toward said jaws, means on the plunger for closing said jaws during said last named movement thereof, means for moving the plunger in the direction of said jaws, said anvil having hook portions for engaging the spread side portions of the scoop, means for moving the plunger and the engaged scoop away from said jaws so as to move the scoop out of contact with the tape, and a stationary wall portion on said tool for limiting said last named movement of the plunger.

3. A hand tool for removing scoops from a separable fastener stringer tape, said tool comprising a member having a handle and a fixed jaw, a second jaw movably supported in said member and adapted to clamp said tape against said fixed jaw adjacent a scoop, a plunger mounted in said member and movable toward and from said jaws, said plunger having a scoop engaging socket for pressing a scoop against the clamped jaws during movement of the plunger toward said jaws, means on said jaws cooperative with said socket for coincidentally splitting said scoop and transferring the scoop from the tape to the socket, means on the socket for retaining the scoop therein during movement of the plunger away from the jaws, and interengaging means on the plunger and said second jaw for clamping and unclamping the jaws during said movement of the plunger toward and from the jaws respectively.

4. A tool for removing scoops from separable fastener stringer tapes comprising a member having a handle and a pair of reversely curved jaws terminating in prongs having inclined diverging surfaces, said jaws being adapted to grasp a stringer tape adjacent a scoop thereon, a plunger mounted in said member and movable toward and from said jaws, said plunger having a scoop engaging socket adjacent said jaws adapted to force said scoop onto said prongs to split the scoop, spring tension means adjacent the other end of said plunger for normally supporting the plunger in spaced relation to said jaws, means comprising a supplemental handle pivotally supported in said member and operatively engaging the plunger for moving the plunger in the direction of said jaws and against the action of said spring, and said socket having hook portions for gripping and removing said scoop from said prongs and said tape during movement of the plunger away from the jaws.
